UNITED STATES PATENT OFFICE

2,191,493

DRILL BIT

John L. Reilly, Claremont, N. H., assignor to
 Sullivan Machinery Company, a corporation
 of Massachusetts

Application February 26, 1936, Serial No. 65,778
 Renewed May 23, 1939

6 Claims. (Cl. 255—64)

My invention relates to drill bits, and is of particular adaptability, as will hereinafter appear, to detachable drill bits.

5 Ease of sharpening and re-sharpening is of great importance with detachable drill bits, as such bits are very commonly used by contractors and others who have no desire to go to the expense of purchasing forging machines for the purpose of re-sharpening their drill bits. Users 10 of detachable bits may employ, at relatively small expense, grinding devices for re-sharpening their bits, and accordingly it is most desirable that a detachable bit be capable of re-sharpening by a grinding device and with a minimum of complication. If it is possible simply to move the bit 15 bodily rectilinearly towards a rotating grinding wheel while maintaining the axis of the bit in a plane including the axis of rotation of the wheel, the simplest possible method of re-sharpening 20 will be attained, as it will be necessary only to move the bit forwardly along such a line to the necessary degree, then to withdraw the bit and rotate it 180° on its axis and again feed it forward against the wheel. Such an operation also results in a bit of very desirable construction and 25 performance characteristics.

It is an object of my invention to provide an improved drill bit, and more particularly to provide an improved drill bit very easy to re-sharpen, very fast cutting and very durable, and therefore 30 especially adapted to detachable drill bit construction. It is another object of my invention to provide a drill bit which can be sharpened with maximum ease with the use of a single grinding wheel, and by relative movement between said bit and the grinding wheel in a direction only normal to the circles of rotation of the periphery of the grinding wheel. It is a further 35 object of my invention to provide a drill bit which may be re-sharpened also by a swinging movement of the grinding wheel about an axis at right angles to the axial line of the bit. It is still another object of my invention to provide an improved drill bit which will cut away the stone 40 very effectively across the inner portions of the hole and also chop away the stone at the outer edge or periphery of the hole, and through the use of chopping edges both reduce and compensate for any possible wear of the extremities of 45 the cutting edge or edges of the bit. Further objects and advantages of the invention will hereinafter more fully appear.

In the accompanying drawing in which one form which my invention may assume in practice 50 has been illustrated:

Fig. 1 is a side view of the forward end of a drill bit constructed in accordance with the illustrative embodiment of the invention.

Fig. 2 is a similar view taken at right angles to 55 Fig. 1.

Fig. 3 is a front end elevation of the bit.

Fig. 4 is a section through the bit on the plane of the line 4—4 of Fig. 1.

Fig. 5 is an axial section through the bit on the plane of the line 5—5 of Fig. 2. 5

Fig. 6 is a view showing the sharpening of a bit constructed in accordance with the invention, and

Fig. 7 is a sectional view showing a sharpening operation, the section being taken on the plane 10 of the line 7—7 of Fig. 6.

Referring now to the drawing, it will be observed that I have illustrated my improved drill bit construction as embodied in a detachable drill bit 1 adapted to be suitably secured as by threads 15 2 to the forward end of a drill steel shank. The drill bit is provided with pairs of diametrically opposite wings, the wings of one pair being disposed at right angles to the wings of the other. Two of these wings, marked 3 and 4, may be narrower than the other wings 5 and 6, but it is not imperative that this size relationship prevail. It is commonly desirable to provide for the supply 20 of cleansing fluid through the drill bit to the bottom of the hole, and for that reason a cleansing fluid supply passage 7 may be provided. Herein 25 this is shown as opening through the forward end of the bit at the center thereof. The wings 3 and 4 support cutting edges 8 and 9, these edges lying in a common arc, as illustrated at 10 in Fig. 1. Chopping edges 11 and 12 are formed at or near 30 the outer ends of the wings 6 and 5, these chopping edges being preferably formed a small distance inside the extremities of these wings, as by 35 beveling at 14, so that the risk of fracturing or chipping off the chopping edges will be materially reduced. The forward end of the bit is formed by surfaces whose elements in planes parallel to the diametric plane including the arc 10 are all 40 arcs. At right angles to these planes there are surface elements which are straight lines, though that is not essential. As a result, it will be noted that the forward surfaces 18 and 19 of the wings 6 and 5 respectively are hollow ground, as it were. The opposite extremities of the cutting edges 9 45 and 8, denoted by 20 and 21 in the drawing, will be observed to project forwardly further than any other portions of the drill bit, in the specific embodiment shown.

By appropriately determining either the diameter of the grinding wheel, or its radius of arcuate movement, or the radius of arcuate movement of the bit relative to the wheel, depending upon the method of sharpening employed, the curvature at 22 at the periphery of the chopping wings 5 and 6 55 may be caused to conform almost perfectly to the desired arc, so to speak. That is to say, the chopping edge may be largely maintained in a cylinder whose diameter is equal to the diametric distance between the points 20 and 21. Different 60

methods of re-sharpening and of initially sharpening a bit of this character may be employed. The peripheral surface of the bit as at 23 may be essentially conical, and the sharpening of the bit may be accomplished as illustrated in Figs. 6 and 7 by the employment of a grinding wheel having frusto-conical grinding surfaces 24 and 25, and advancing the bit toward the wheel along an axial line 27, 26, thereby forming, say the surface 18 and the corresponding surface 28 of the front of the bit, then withdrawing the bit along the line 26, 27 and turning it through 180° on its axis and again advancing it toward the wheel, and thereby causing the surface 24 of the wheel to form the surface 19 and the surface 25 of the wheel to form the surface 29 of the bit, as shown in Fig. 6. For this operation, the diameter of the wheel should be made such that the curvature of the periphery of the wheel will produce the desired curvature of the face of the bit.

A smaller wheel may be used, if desired, and the wheel may be swung about an axis perpendicular to the axial line 26, 27 and in advance of the bit, the arcs of motion of the wheel conforming to the desired arcs to be formed on the surfaces 18, 28 and 19, 29; or the wheel may be held stationary and the bit itself moved bodily about an axis forward of the bit, the path of the bit being then determined to produce the desired curvature of the surfaces 18, 28 and 19, 29. Of course, in either of the methods last described the bit will be rotated between successive grinding operations on its axial line. Of course annealing would permit the use of milling cutters instead of grinding wheels, and this falls within the contemplation of my invention.

The bit which results from these operations will obviously be a fast cutter, durable, despite the projection of the points 20 and 21, because of the presence of the chopping edges 5 and 6, most easily re-sharpened, and highly desirable for the purposes for which it is intended. A particular advantage resides in the fact that the bit cuts a hole larger than its own diameter, so that there results a hole larger than would come from the use of prior standard forms of bit of the same gauges.

While I have in this application specifically described one form which the invention may assume in practice, it will be understood that this form of the same is shown for purposes of illustration and that the invention may be modified and embodied in various other forms without departing from the spirit or the scope of the appended claims.

What I claim as new and desire to secure by Letters Patent is:

1. A drill bit having wings arranged in diametrically aligned pairs, with the diametric lines of said pairs at right angles to each other, one of said pairs of wings having cutting edges extending radially therealong and the other of said wings having chopping edges at the outer extremities thereof, substantially the entire forward end of said bit formed by surfaces struck on arcs about an axis in advance of said bit and said bit having a longitudinal section at its forward end, on a diametric plane including such axis, terminating in a pair of forwardly opening angles.

2. A drill bit having wings arranged in diametrically aligned pairs with the diametric lines of said pairs at right angles to each other, one

of said pairs of wings having diametrically aligned edges in a common arc struck from a center in advance of the bit, said other wings having adjacent their extremities arcuate chopping edges, and the forward surfaces of said bit between said diametrically aligned edges and each of said chopping edges conforming to frusto-conical surfaces struck about an axis disposed in advance of the bit and perpendicular to a line including the bit axis.

3. A drill bit provided with chopping portions having arcuate chopping edges and concave forward chopping faces, and a cutting edge lying in a diametric line midway between said chopping edges, said cutting edge and said forward chopping faces being curved on arcs struck from centers which lie in a common straight line, and the extremities of said cutting edge at the bit periphery projecting in advance of said chopping edges.

4. A drill bit having radially extending cutting edges and chopping edges disposed at opposite sides of the line including said cutting edges, substantially the entire forward surface of said bit lying in four frusto-conical surfaces whose axes are aligned and lie in a line perpendicular to the bit axis extended, the outer extremities of said cutting edges and the chopping edges lying substantially in a surface of a cylinder whose axis is coincident with the bit axis.

5. A drill bit having wings arranged in diametrically aligned pairs, with the diametric lines of said pairs at right angles to each other, one of said pairs of wings having aligned edges in a common arc struck from a center in advance of the bit, and the other pair of wings having chopping edges which lie in the surface of a cylinder of a diameter substantially equal to but slightly less than the distance between the extreme points in said aligned edges and each of which also lies in a substantially conical surface whose axis is perpendicular to the bit axis extended.

6. A drill bit having wings of like radial dimension arranged in diametrically aligned pairs with the diametric lines of said pairs at right angles to each other, one of said pairs of wings having aligned edges in a common arc and said other wings having adjacent their extremities arcuate chopping edges, the forward portions of the former pair of wings terminating in and supporting said aligned edges and conforming to surfaces of revolution whose axis is in advance of said aligned edges and perpendicular to a plane including said aligned edges at a point in said plane through which the center line, extended, of said bit passes, and the portions of said other wings inwardly of said chopping edges cut back progressively towards the axis of the bit to provide arcuate surfaces of revolution at the forward end of the last mentioned wings whose axis coincides with the axis first mentioned and which arcuate surfaces extend to the rearmost portions of said first mentioned surfaces of revolution, said bit symmetrical in central section on a plane perpendicular to said first mentioned plane, whereby the complete forward end of said bit between said chopping edges may be formed by effecting successive grinding relations of the portions of the bit at opposite sides of the aligned edges with a generally V-formed wheel along lines radial of the wheel.

JOHN L. REILLY.
